Primary Examiner — Sheryl Lane*Assistant Examiner* — Mark T. Philippi(74) *Attorney, Agent, or Firm* — Raymond A. Nuzzo(57) **CLAIM**

The ornamental design for an ice press, as shown and described.

DESCRIPTION

FIG. 1 is a front elevational view of an ice press showing my new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a rear elevational view thereof; and,

FIG. 7 is a top perspective view thereof.

In the drawings, the broken lines are for the purpose of illustrating portions of the ice press that form no part of the claimed design.
